4 Claims. (Cl. 12—33.4)

1

This invention relates to a machine for sticking soles, particularly leather soles, to boots and shoes and comprises an improved machine adapted to support a boot or shoe in an inverted position so that its sole is readily accessible, and designed to stick a sole firmly to the shoe, particularly at its edges, to preserve the desirable arched contour of the boot or shoe bottom, and to prevent distortion by upward or downward bending of the edge of the sole when pressure is applied for sticking the sole to the boot or shoe.

A machine according to the invention comprises a base adapted to support a boot or shoe so that its sole faces upwards, and a press member adapted to press a sole onto the boot or shoe, and has right-hand and left-hand retractable supporting devices, which have tongues adapted to project into the space between the upper of the boot or shoe and the projecting edge of the sole, and which are slidably mounted on the base at opposite sides of the boot or shoe, so that they can be adjusted to positions in which the tongues engage the boot or shoe and provide a rigid support for the edges of the sole against the pressure of the press member.

For use in soling boots and shoes of a number of different shapes and sizes, the machine is provided with groups of fingers instead of plates, each group being composed of contiguous parallel-sided individually adjustable fingers formed with inwardly projecting tongues which co-operate to form a continuous support for the welt or edge of the sole. This construction enables the machine to be readily adjusted to suit a range of different sizes of boots or shoes.

The invention includes an improved press member for pressing the sole onto the shoe which is adapted to exert pressure on the middle of the sole at first, but which yields at its middle part so that the pressure spreads outwards as the load increases, and so that the final pressure applied is greater at the edges of the sole than at the middle parts thereof.

Other features of the invention will appear from the following more detailed description of one example of a machine constructed according to the invention reference being made to the accompanying illustrative drawings in which:

Figure 1 is a side elevation of the machine,

Figure 2 is a plan view of the machine, the left-hand side of the machine being shown with its press member and operating mechanism removed, and the right-hand side being shown with the press-operating lever pulled down and with the sole-edge supporting devices removed,

2

Figure 3 is a plan view of a complete set of devices for supporting the projecting edges of the sole of one boot or shoe,

Figure 4 is a side elevation of the structure shown in Figure 3,

Figures 5, 6, 7 and 8 are fragmentary sectional views taken respectively on the lines V—V, VI—VI, VII—VII and VIII—VIII, Fig. 3 and illustrating the shapes of the tongues formed on certain of the fingers shown in Figure 3,

Figures 9 and 10 are side-elevational and plan views respectively of a retractable finger used in the mechanism shown in Figures 1, 2 and 3,

Figures 11 and 12 are views similar to Figures 9 and 10 of an adjacent finger having cam surfaces adapted to co-operate with corresponding cam surfaces on the finger shown in Figures 9 and 10.

Figure 13 is a side elevation of a pressure pad, 20 and

Figure 14 is an end view of the pressure pad.

The machine shown in the drawings comprises a double base-frame 1 carrying two complete sets of mechanism, one of which is adapted for soling 25 the left boot or shoe of a pair, whilst the other is adapted for soling the right boot or shoe. Each half of the machine is thus complete in itself, and it will be necessary to describe only one of them. Parts of the right-hand half of the machine shown in Figure 2 are marked with the same reference numerals as the corresponding parts of the left-hand half of the machine, but are distinguished by the suffix, "a."

As can be seen from Figures 1 and 2, each half 35 of the main frame or base 1 of the machine is of box-like shape, open at the top, and contains an adjustable heel-support 2 and an adjustable toe-support 3 adapted to support a lasted boot or shoe so that its sole faces upwards and projects somewhat above the sides 5 of the base or frame.

For additionally supporting the boot or shoe, the machine is provided with a right-hand group of fingers 6 and a left-hand group of fingers 7 supported on the sides 5 of the base or frame 1 45 in such a way that they are horizontally slidable towards and away from the boot or shoe. Each of the groups 6 and 7 is composed of a number of contiguous parallel-sided individually slidable fingers formed with inwardly projecting tongues 8 which co-operate to form a substantially continuous support for the welt or edge of the sole. These fingers are individually adjustable inwards and outwards to adapt the machine to suit a range of different sizes of boots or shoes with 55 the same fingers. Moreover, the groups of fingers

are interchangeable with different groups to suit further ranges of size or shape outside the range of adjustment of a single group of fingers. For example, one group of fingers may be designed to suit a range of men's sizes and another group may be designed to suit a range of women's sizes. To enable women's shoes of different styles involving considerable variation of profile, two or more sets of fingers for different range of women's boots or shoes may be required. The fingers on each side of the machine have flat undersurfaces 9 adapted to bear against a flat supporting surface 10 provided for them on the side wall 5 of the frame or base of the machine; and they are held together by a carrier-bar 11 formed with a longitudinal slot 12 into which the fingers fit slidably, the carrier bar being received by a locating groove 13 provided for it in the side wall 5 of the frame or base of the machine. Each carrier-bar carries a clamping-screw 14 at one end by which the fingers can be clamped against the opposite end 15 of the slot 12 and thus held fast after they have been adjusted.

To give adequate support for the projecting edge of the sole at the tip of the toe, it has been found advantageous to provide a supporting member additional to the right-hand and left-hand fingers 6 and 7 described above, this additional member being in the form of a bar 16, which extends across the space between the side walls 5 of the frame or base and makes sliding contact with the foremost finger of each of the right-hand and left-hand sets. The ends of this bar, which will be referred to below as a toe-bar, may engage in the ends of the slots 12 in the carrier-bars 11 described above, or it may be bolted or otherwise rigidly fixed to the carrier bars. The toe-bar is formed between its ends with recesses 17 shaped to receive the toe-parts of the sole and upper and separated by a straight-edge tongue 18 adapted to engage between the upper and the projecting edge of the sole. The edge of the tongue 18 lies in the same plane as the face of the toe-bar that is in contact with the foremost fingers of the right-hand and left-hand sets of fingers 6 and 7. The tongue 18 co-operates with the tongues 8 to form a continuous support for the projecting edge of the sole 11 all around the toe of the boot or shoe.

The machine is provided with a heel-post 19 which has a screw or other adjustment means by which it can be raised or lowered to bring the last to the proper level. The toe support 3 is in the form of a pad attached to a vertically adjustable toe-post 20 by means of a ball or similar joint 21 so that the toe-pad 3 is self-aligning. The adjusting mechanism for the toe-post consists of an adjustable wedge 22 having a transverse sliding movement for raising or lowering the post 20. The heel and toe supports are thus readily adjustable for the purpose of adjusting the last so that it co-operates with the toe-bar 16 and right-hand and left-hand fingers 6 and 7 to provide a rigid support that conforms to the curvature of the sole as lasted. Consequently, when pressure is applied, as hereinafter described, the sole will not be distorted by any upward or downward bending of its edges.

For pressing a sole onto the shoe after it has been positioned on the supports described above, the machine is provided with a press-plate 23 carried by an arm 24 attached to a hinge 25 at the rear of the machine and adapted to swing down into an approximately horizontal position for bringing a pressure pad 26 into engagement

with the sole. The pressure pad 26 consists of a block of hard rubber or similar resilient material, which may be of generally rectangular shape as seen in plan, and which is attached to a back-plate 27 adapted to slide into position on the press-plate 23, the pad 26 being thus readily detachable. The lower surface 28 of the pad is of curved shape corresponding to the curvature of the correctly-lasted sole, but adapted to exert pressure on the middle of the sole at first, the pressure spreading outwards as the load is increased, thereby expelling air pockets between the sole and welt. The upper surface of the pad has a concavity 29 in a region corresponding to the middle area of the sole so that this part of the pad will yield somewhat as the pressure increases, and so that the final pressure applied will be greater at the edges of the sole than at the middle parts thereof.

The machine includes a lever-operated mechanism for actuating the arm 24 which is capable of swinging the arm upwards through a considerable angle of say 60° or more so as to lift the pressure pad 26 well away from the boot or shoe and allow easy access to boot or shoe and its supporting mechanism. For this purpose an operating lever 30 is fulcrumed at a point 31 below and in front of the fulcrum 25 of the arm 24 and extends upwards to a point above the arm 24, the lever being forked so that the arm 24 can swing freely through it. A pivoted toggle link 32 is attached at one end to the lever 30, and at the other end to the arm 24 at a point chosen so that the toggle passes through a dead-centre position (in which the pivots of the link 32 are aligned with the fulcrum 31 of the lever 30), just before the arm 24 reaches an approximately horizontal position. The press-plate 23 is attached to the arm 24 by means of an adjusting screw 33 which enables the pressure attained in the locked position of the toggle link to be readily adjusted. The press-plate 23 engages the adjusting screw by a ball or similar joint 34 located over a desired centre of pressure of the pressure pad (corresponding to the centre of the sole) so that the press-plate aligns itself automatically in such manner as to apply pressure substantially evenly all round the edges of the sole. The press plate may conveniently be attached to the arm by a pair of spring-loaded tie-bolts 35 located one in front of and one behind the ball joint 34 and arranged to hold the two parts of the joint together under spring pressure. One or more tension springs may be arranged to assist the rearward swinging movement of the operating lever 30 by which the press-plate arm is swung up to lift the pressure-pad clear of the work when the toggle has been broken.

It has been found that in a machine fitted with right-hand and left-hand sets of fingers 6 and 7 as described above, it is advantageous to provide one or more particular fingers (marked 36, 37 and 38 in Figure 2) so placed that they have merely to be retracted to allow the remaining fingers to be closed together to suit boots or shoes of smaller sizes. The machine can thus be very quickly adjusted to suit boots or shoes of a range of different sizes by merely inserting or withdrawing the particular fingers provided for that purpose. To enable the fingers 36, 37 and 38 to be retracted from their operative positions without being actually removed from the machine, these fingers and the fingers next to them may be formed with ramps and co-operating recesses which allow the fingers next to the

fingers 36, 37 and 38 to move closer together so that their tongues meet and completely close the gaps left between them when the fingers 36, 37 and 38 are retracted. The arrangement of these ramps and recesses will be understood from Figures 9 to 12 of the drawings; Figures 9 and 10 show the finger 36 and Figures 11 and 12 show the adjacent finger marked 39 in Figure 3. As shown in Figures 9 to 12, the finger 36 is formed at its forward end with a ramp 40 located below the tongue 8 of the finger. It also has a recess 41 the rear wall of which forms a ramp 42. The finger 39 has a ramp 43 adapted to co-operate with the ramp 36 and a recess 44 one wall of which forms a ramp 45 adapted to co-operate with the ramp 40 when the finger 36 is retracted, the ramp 40 slides down the ramp 45 and into the recess 44 and the ramp 43 slides down the ramp 42 and into the recess 36, thus allowing the fingers marked 39 and 46 in Figure 3 to move closer together and to close the gap left by the withdrawal of the tongue 8 of the finger 36.

It has been found advantageous to extend the locating grooves 13 provided in the side walls 5 of the frame or base so that the carrier-bars 11 that carry the right-hand and left-hand plates or fingers 6 and 7 and the toe-bar 16 are freely slideable therein and can thus be adjusted forwards or backwards. The support for the projecting edges of the sole is thus bodily movable forwards or backwards. This enables it to be readily adjusted, after its length has been increased or diminished by the insertion or withdrawal of the fingers, 36, 37 and 38, so that it will register correctly with the curved surface of the pressure pad 26, i. e. so that the convex surface of the sole as supported by the last and by the right-hand and left-hand fingers 6 and 7 fits the corresponding concave surface 28 of the pressure pad 26. The heel support 2 for the last may be a flat bolt-head or other support that will allow the last to move horizontally so that the final position of the lasted shoe is determined by the position of the fingers 6 and 7, the toe and heel supports serving merely to steady the last and to take part of the pressure applied by the pressure pad 26.

In the use of the machine, the boot or shoe is supported as described and a sole is then stuck onto the shoe by means of a suitable adhesive applied at the edges and adjacent marginal parts of the sole only, leaving the middle area of the sole free of adhesive. Pressure is applied by swinging down the operating lever 30 until the toggle linkage locks, this pressure being maintained until the adhesive has set sufficiently. The pressure is then released and the pressure pad 26 is moved quickly out of the way by merely swinging the operating lever 30 upwards and backwards.

It will be readily understood that the machine can be adapted for sticking on half-soles or full-length soles as may be required either for repairing boots or shoes or in the manufacture of new boots or shoes.

The pressure pad 26 may be of greater length and width than the sole, and the same pad may be used for boots and shoes of different sizes that will fit its curved surface 28.

The provision of a firm support for the welt or projecting edge of the sole during the process of sticking on a sole in accordance with the invention enables the sole to be firmly secured by the use of adhesive at the edges and adjacent marginal parts of the sole only, leaving the middle

area of the sole free of adhesive. This not only prevents the undesirable stiffening of the sole that would occur if the outside were made adherent to the insole over the whole of its surface, but preserves the desirable "breathing" properties of a leather sole by leaving a middle area of the sole free from adhesive and thus preserving its porosity.

The invention is not restricted to welted boots and shoes and can be used for sticking soles to ladies single-sole shoes and other shoes not provided with welts.

We claim:

1. A machine for sticking soles to boots and shoes, comprising supporting means for a lasted boot or shoe, a plurality of contiguous fingers adapted to enter the welt crease of a boot or shoe positioned on said shoe supporting means, and co-operating recesses and ramps formed on adjacent longitudinal surfaces of at least two of said fingers, whereby upon partial retraction of one of said fingers, the other of said fingers can be moved transversely to close the gap between the welt-engaging portions of the fingers flanking said retracted finger.
2. A machine for sticking soles to boots and shoes, comprising supporting means for a lasted boot or shoe, welt supports comprising two sets of contiguous inwardly directed fingers forming a pair of substantially continuous supports for the right hand and left hand welt edges of the boot or shoe, the fingers of each set being individually adjustable to adapt the welt supports for boots and shoes of different shapes and sizes, and a toe-bar extending transversely across the machine for engagement at its ends by the right hand and left hand welt supports, a recess in said toe-bar between its ends to receive the toe of the boot or shoe and a straight edged tongue formed by said recess to engage between the upper and the projecting edge of the welt at the toe of the boot or shoe, the edge of the tongue lying in the same plane as the face of the toe-bar that is in contact with the right hand and left hand welt supports.
3. A machine for sticking soles to boots and shoes, comprising supporting means for a lasted boot or shoe, welt supports comprising two sets of contiguous inwardly directed fingers forming a pair of substantially continuous supports for the right hand and left hand welt edges of the boot or shoe, the fingers of each set being individually adjustable to adapt the welt supports for boots and shoes of different shapes and sizes, a longitudinally slotted carrier bar for each set of fingers which are transversely slideable in the slot of said bar, means for clamping the fingers against one end of said slot, and a supplementary support for the toe part of the boot or shoe welt.
4. A machine for sticking soles to boots and shoes, comprising supporting means for a lasted boot or shoe, welt supports comprising two sets of contiguous inwardly directed fingers forming a pair of substantially continuous supports for the right hand and left hand welt edges of the boot or shoe, the fingers of each set being individually adjustable to adapt the welt supports for boots and shoes of different shapes and sizes, a longitudinally slotted carrier bar for each set of fingers which are transversely slideable in the slot of said bar, means for clamping the fingers against one end of said slot, a supplementary support for the toe part of the boot or shoe welt, said supplementary support comprising a toe-bar extending transversely across the machine for

engagement at its ends by the right hand and left hand welt supports, a recess in said toe-bar between its ends to receive the toe of the boot or shoe; a straight edged tongue formed by said recess to engage between the upper and the projecting edge of the sole at the toe of the boot or shoe; the edge of the tongue lying in the same plane as the face of the toe-bar that is in contact with the right hand and left hand welt supports, a pivoted pressure-applying arm by 10 which a pressure pad is carried, including means permitting self-alignment of the latter during a pressing operation, and lever operated toggle mechanism for said arm, whereby a greatly increased mechanical advantage is achieved at 15 the end of said pressing operation.
